UNITED STATES PATENT OFFICE.

BERT A. HARE, OF BRADFORD, PENNSYLVANIA.

OIL-WELL STRAINER.

1,276,213.

Specification of Letters Patent. Patented Aug. 20, 1918.

Application filed January 10, 1918. Serial No. 211,157.

To all whom it may concern:

Be it known that I, BERT A. HARE, a citizen of the United States, residing at Bradford, in the county of McKean and State of 5 Pennsylvania, have invented certain new and useful Improvements in Oil-Well Strainers, of which the following is a specification.

This invention relates to improvements in 10 means for applying strainers to the suction apertures of pumping apparatus used in oil wells and the like wherein oil and other liquids are pumped from wells of extended depths.

15 One of the objects of the invention is to provide a strainer which will exclude from the pump cylinder all sand, particles of rock and other abrasive substances, which have a tendency to cut and destroy the plunger, 20 valves and valve seats of the actuating mechanism of the pump, without lessening the volume of the liquid flow to the suction port of the pump necessary to carry out the full functioning of the pumping apparatus.

25 Another advantage gained by the novel construction and the arrangement of the parts comprising the screening means, resides in positioning the screen fabric in a pocketed enclosure wholly inside of the 30 periphery of the screen barrel, where it is protected from injurious contact with the side walls of the well.

This forms an important feature in connection with pumping wells of considerable 35 depth, where through the reciprocal movement of the pump rods, actuating the pump plunger, there is caused a like movement to the screen barrel of sufficient effect to cause a chafing away of the screen mesh, when it 40 has a bearing contact with the walls of the well.

Another advantage possessed by my improved device, is that it is provided with means whereby it can be located at any desired point in the line of tubing used in 45 pumping wells, and positioned at any desired distance from the working barrel comprising the oil elevating means.

Other and further objects and advantages 50 of the invention will be hereinafter set forth, and illustrated in the accompanying drawings, wherein:

Figure 1, is a side elevation of the strainer barrel.

Fig. 2, is a central vertical section through 55 the strainer barrel and the contiguous parts.

Fig. 3, is a transverse section through the strainer barrel.

Like numerals of reference denote like parts throughout the several views of the 60 drawings.

Referring to the drawings, 5 represents the strainer barrel formed of any suitable metal, such as cast iron or steel where cheapness of manufacture is desired or of brass, 65 bronze or other non-ferrous metal where a non-corrosive medium is desired.

The barrel 5 is formed with a conduit or passageway 8 longitudinally thereof, and is provided with screw threads at each end for 70 the purpose of connecting the same to the working barrel of the pump at the one end, and to the anchor at the other.

Located on opposite sides of the barrel 5 are rectangularly shaped sunken pockets 6. 75 Extending from the bottom of the pocket 6 is a rectangularly shaped port 7, communicating with the longitudinal passage 8. Located between the side walls of the pocket 6 and the port 7, are horizontally disposed ledges 9, extending in rectangular formation around the port 7. Located within the pocket 6, and covering the port 7, is a screening medium 10, comprising a wire mesh formed of non-corrosive material. The outer edges of the wire mesh 10, rest upon and are attached to the ledges 9, of the pocket 6, by the compressing frame 11, adapted to reside over the ledges 9 in the pocket 6, and having an opening adapted 80 to register with the port 7. The frame 11 is attached to the ledges 9, by suitable fastenings comprising the screws 12 passing through the frame 11 and the mesh 10 and screw threaded into the ledges 9. 95

For the purpose of making a sealed joint, the gasket 13 is placed between the frame 11 and the wire mesh 10, which effectively 100 closes the passage way to all fluids except through the wire mesh 10.

It is to be understood that the number of screened apertures in the barrel 5, may be varied according to the requirements; for general purposes the number shown in the drawings will be adequate.

By the novel arrangement and the application of the component parts, the screening means, comprising the wire mesh, can easily

and quickly be removed for replacement, and due to its location inside of the circumferential line 14, (Fig. 3) of the exterior of the screen barrel 5 it is well protected from 6 injury and wear.

It is well understood by those skilled in the art, that it is often desirable to locate the suction ports of an oil well pumping medium, at a given distance from the bottom of the well; it is also desirable to locate the suction ports at a given point below the working barrel of the pumping apparatus, varying according to the conditions of the oil bearing strata through which the well is drilled. To provide for these conditions, varying in different wells I have provided the exteriorly formed thread A on the one end of the screen barrel 5, and the interiorly formed thread B on the other end.

When it is desired to tube a well at the top of the oil bearing strata, or sand, to keep it flooded with oil, a section of tubing is used between the barrel screen 5, and the working barrel, long enough to locate the working barrel at the top of the sand while the screen barrel 5 resides at the bottom of the sand, and to support the screen barrel 5 in proper position, a section of tubing closed at the lower end and known in the art as the anchor, is connected to the screen barrel 5 by the thread A, and extends therefrom to the bottom of the well.

When it is desired to tube a well to the bottom of the sand the screen barrel 5, is connected directly to the working barrel by the thread A, and the anchor is attached to

thread B. The threads A and B, being interchangeable with the threaded connections on the tubing used, the screen barrel 5 can be located in any desired place in the tubing in relation to the oil bearing strata through which the well is drilled.

What I claim and desire to secure by U. S. Letters Patent is:

1. An oil-well strainer of the character described, comprising a tubular shell having a plurality of apertures located in the sides thereof, screening means covering said apertures, retaining means covering the edges of the screening means and a compressible medium located between the screening means and the retaining means.
2. An apparatus of the character described, comprising a tubular shell, longitudinally extended pockets located below the outer surface of said shell, apertures extending from said pockets to the inner wall of said shell, ledges formed in said pockets surrounding said apertures, and screening means resting on said ledges covering said apertures, retaining means for holding said screening means in place, and a compressible medium located between the screening means and the retaining means with means for compressing the same against the screening means.

In testimony whereof I have affixed my signature in the presence of two witnesses.

BERT A. HARE.
